UNITED STATES PATENT OFFICE.

WILLIAM E. WENTWORTH, OF SAN ANTONIO, TEXAS.

PUMP JACK.

Application filed July 13, 1926. Serial No. 122,223.

This invention relates to improvements in pump jacks and has as its general object to provide a pump jack which will be steady and positive in its operation and simple in construction, and which will embody means whereby the stroke of the pump rod may be varied as occasion requires.

Another object of the invention is to provide a pump jack which may be operatively connected with the pump rod regardless of the distance to which the rod extends above the ground surface, thereby obviating adjustment which would otherwise be required in operatively assembling the pump jack with the said rod.

In the accompanying drawings:

Figure 1 is a side elevation of the pump jack embodying the invention.

Figure 2 is a front elevation of the lower portion of the pump jack.

Figure 3 is a detail plan view of the upper end of the swinging post of the jack and the connection provided between the same and the flexible element which leads to the pump rod.

Figure 4 is a detail horizontal sectional view taken substantially on the line 4—4 of Figure 1, looking in the direction indicated by the arrows.

Figure 5 is a similar view on the line 5—5 of Figure 1, looking in the direction indicated by the arrows.

Figure 6 is a detail horizontal sectional view on the line 6—6 of Figure 1, looking in the direction indicated by the arrows.

Figure 7 is a similar view on the line 7—7 of Figure 1, illustrating the connection between the flexible motion transmitting member of the jack and the pump rod to be reciprocated.

The jack embodying the invention comprises a pair of base sills 1 which are preferably embedded in the ground adjacent the pump casing 2 and upon which sills are mounted base plates 3 and 4 bolted or otherwise secured in place and supporting the parts comprising the structure, the plates serving likewise to relatively brace the said sills, so that the structure will be supported in a substantial manner. The numeral 5 indicates in general an upright comprising a pair of channel beams between the lower ends of which there is bolted or otherwise secured the flat-sided shank 7 of a pivot member 8 which is provided at the lower end of its shank with shoulders 9 upon

which the lower ends of the said channel beams rest, as clearly shown in Figures 1 and 2 of the drawings. The pivot member 8 is disposed between two bearings 10 which are cast upon the plate 3, and a short shaft 11 is journaled in the said bearings and extends through an opening in the said pivot member 8 so as to support the upright comprising the channel beams 6 normally in an upright position and yet permit of downward swinging movement thereof under conditions to be presently explained. Disposed between the upper portions of the beams and bolted or otherwise secured in place, is a head 12 having shoulders 13 at its opposite sides engaging the rear sides of the channel members 6, the head 12 being formed with a pair of spaced ears 14. The numeral 15 indicates a brace for maintaining the upright 5 in vertical position, and this brace comprises an eye beam the web of which is cut away at its upper end so as to accommodate the ears 14, a pivot bolt 16 being fitted through the side flanges of the eye beam at the said upper end thereof and through the said ears, as clearly shown in Figure 4 of the drawings. The lower end of the brace 15 has its web cut away in a similar manner so that its side flanges at its said end will straddle spaced ears 17 which are integrally formed upon the base plate 4 and extend forwardly therefrom, a bolt 18 being fitted through the said ears 17 and through the said flanges of the brace 15, as shown in Figure 5, so as to secure the said end of the brace to the base plate.

Bearings 19 are formed upon the base plate 4, and a shaft 20 is journaled in the said bearings and extends through aligned openings in plates 21 which are bolted, as at 22, to the opposite sides of a rocking beam 23, the said plates having side flanges 24 engaging the opposite edges of the said beam. The numeral 24' indicates in general a saddle member which is mounted at the upper end of the rocking beam 23 and comprises a body 25 having spaced ears 26 straddling the rear edge of the said beam 23 at its upper end, a bolt 27 being fitted through the said ears and through said beam to secure the body 25 to the beam. The body is formed with a transverse recess or seat 28 in which is engaged one end of a rectangular link 29, and a hook 30 is connected to the other end of the link, the link straddling the upper end of the beam, and

one rod 31 of an adjustable connection comprising a threaded rod 32 and a turn-buckle 33, is secured to the shank of the said hook 30, the rod 32 of the adjustable connection being connected as at 34, to one end of a sprocket chain which is indicated by the numeral 35 and which passes about a sprocket gear 36 mounted upon a shaft 37 journaled in bearings 38 secured in the channels of the members 6 of the upright 5 at their upper ends. The other end of the sprocket chain 35 is connected, in a manner which will now be described, with the pump rod, which is indicated by the numeral 39.

15 The means provided for connecting the last mentioned end of the chain 35 with the pump rod 39 comprises a clamp consisting of a member 40 which is provided in one side with an approximately semi-cylindrical recess or seat 41 to embrace one side of the said pump rod 39, and the said member is provided with a pair of upstanding ears 42 between which and an intermediate upstanding portion 43, the leaves of the lower 20 most link of said chain at its said end are received, these leaves being indicated by the numeral 44. A bolt 45 is fitted through the said ears and the said portion 43 and likewise through the link leaves and serves to 25 connect the chain to the said clamp member. The other member of the clamp, indicated by the numeral 46, is likewise provided with an approximately semi-cylindrical seat 47 to embrace the other side of the said pump rod, 30 and bolts 48 are secured through the said members 40 and 46 and are tightened to clamp the rod. The numeral 49 indicates an eye member is connected with the chain 35 above the clamp just described, and this 35 eye member accommodates a portion of the rod above that portion which is engaged between the clamping members 40 and 46, and in this manner, the chain is adapted to have a substantially rigid two-point connection 40 with the rod so as to insure of steady vertical reciprocation thereof, and it will be understood at this point that the means provided for connecting the chain to the rod permits of adaptation of the chain to pump rods 45 regardless of the distance to which they extend above the upper end of the pump casting, so that an adjustment is provided at this point obviating the necessity of making the adjustment at the point of location of the 50 turnbuckle 33, this latter adjustment being made use of after the chain has been connected with the pump rod, if it should be found necessary to effect further very slight adjustment.

55 The numeral 50 indicates in general a saddle member corresponding to the saddle member 24', and this said saddle member 50 is provided with spaced ears 51 which straddle the forward edge of the upright beam 28, a bolt 52 being fitted through the said 60 ears and interchangeably through openings 53 formed in the said beam 23. The body of the saddle member 50 is formed in its upper side with a seat 54 in which is engaged one end of a link 55 of the same 70 formation as the link 29, and a hook 56 is engaged with the other end of the link and has connected to it one end of the cable 57 which leads to the usual operating means for the jack (not shown). At this point it 75 will be evident that by vertically adjusting the saddle 50 upon the rocking beam 53, the throw of the beam may be adjusted so as to vary the length of the stroke imparted to the pump rod 39.

80 From the foregoing description of the invention it will be seen that there is provided an exceptionally substantial and durable construction of pump jack which will operate to impart a steady reciprocatory motion to the pump rod with which it is connected and the throw of the rocking beam of which jack may be conveniently varied so as to vary the length of stroke of the pump rod. It will also be evident that when 90 it is desired to pull the well, the jack may be readily folded into compact form by disconnecting the clamp 40 and the eye member 49 from the pump rod, removing the bolt 18 or the bolt 16, either as may be desired or found expedient, lowering the upright 5, and swinging the rocking beam 23 downwardly, so that the parts will all occupy a position extending above the said 95 structure of the device.

100 Having thus described the invention, what I claim is:

1. In a pump jack, base sills, a base plate mounted thereon and connecting the same near one end, bearings upon the said base plate, a shaft mounted in the bearings, a bearing member upon the shaft between said bearings, spaced uprights secured at their lower ends to the said bearing member at opposite sides thereof, a wheel journaled for 110 rotation between the upper ends of the uprights, a bracket having a shank secured between said uprights and side arms extending across the uprights to brace the bracket, a base plate mounted upon the sills near the 115 other ends thereof and connecting the same, a brace connected pivotally at its upper end to said bracket and at its lower end separably connected to the last mentioned base plate, a rocking beam mounted upon 120 the last mentioned base plate, means for imparting rocking motion to the beam, a flexible element connected to the beam and passed over the said wheel, and means carried by the flexible element for connection 125 to a pump rod.
2. In a pump jack, a base structure, an upright mounted thereon, a wheel journaled upon the upright, a beam mounted for rocking movement upon the upright and having a 130

- plurality of openings arranged in a series extending parallel to one edge thereof, a saddle having a portion straddling the other edge of the beam at the upper end thereof and provided with a seat, a fastener extending transversely through the saddle and beam, a link engaged at one end in the seat and straddling the said end of the beam, a flexible element connected to the said link 10 and passing over the said wheel, means carried by the flexible element at the other end thereof for connecting the same to a pump rod, a second saddle disposed to straddle the first mentioned edge of the beam and having openings therein for registration with the openings in the beam selectively, a bolt fitted through the openings in the second mentioned saddle and interchangeably in the openings in the said beam, the saddle 15 having a seat, and a link engaged at one end in the seat in the second mentioned saddle and straddling the beam for the connection thereto of means for imparting rocking motion to the said beam.
- 20 3. In a pump jack, an upright, a wheel mounted thereon, a rocking beam, means for imparting rocking motion to the beam, a flexible element connected to the rocking beam and trained over said wheel, a clamp at the lower end of the said flexible element 25 for connection with a pump rod to clamp the same at a point in its length, and a member carried by the flexible element and spaced above the clamp to engage the said pump rod at a point above the point at 30 which it is engaged by the clamp.
4. In a pump jack, an upright, a sprocket gear mounted for rotation at the upper end of the upright, a rocking beam mounted at its lower end for oscillatory movement in 35 spaced relation to the upright, a saddle adjustably mounted on said beam, a sprocket chain trained about the sprocket gear, means at one end of said chain clamping the same to a pump rod, a link disposed about said beam and engaged with the saddle, means connected with the chain and detachably engaging said link at the opposite side of the beam from said saddle, and means for 40 oscillating the said rocking beam.
- 45 5. In testimony whereof I affix my signature.
WILLIAM E. WENTWORTH. [L. s.]
